UNITED STATES PATENT OFFICE.

GEORGE J. BARUCH, OF NEW YORK, N. Y., ASSIGNOR TO KAUFMAN & OBERLEDER, INC., OF NEW YORK, N. Y., A CORPORATION OF NEW YORK.

FUR SCARF.

Application filed February 8, 1928 Serial No. 252,708.

This invention relates to improvements in fur animal heads and has for one of its objects the provision of a novel head of the character referred to adapted to be used on fur 5 scarfs and the like.

Another object of the invention is to produce a head of this nature that is highly ornamental and striking in appearance.

A further object of the invention is to provide a fur animal head of this nature in which the snout, eyes and ears are made of a jewelled 10 fabric.

A still further object of the invention is to provide a jewelled fabric mask adapted to be 15 placed over and secured to a fur scarf head or the like the said mask being made of diamond colored stones, with stones of contrasting colors to accentuate the main features of the animal.

20 Other objects and novel features of my invention will become more apparent as the description proceeds.

In the drawings forming a part of this invention in which similar reference characters 25 are used to describe corresponding parts throughout the several views, and finally pointed out and specifically defined and indicated in the appended claims,

Figure 1 is a perspective view of a portion 30 of a fur scarf, showing my invention as applied thereto.

Figure 2 is a top plan view of my ornamented mask before it is applied to the head.

Figure 3 is a perspective view of a scarf 35 head, showing a modified form of my invention, and

Figure 4 is a detail view of the ear forming section used in the form shown in Fig. 3.

Referring now to the drawings in detail, 5 40 indicates the body portion of a fur scarf provided with a head 6, having ears 7 projecting therefrom.

It is a well known fact that the fur on animal heads employed in the making of scarfs is 45 very thin and sparse, as it nears the snout. This, in many instances gives a cheapening and ugly appearance to the scarf. To overcome this defect, I provide a mask 8 made of a fabric studded generally with jewels 9 preferably of imitation diamonds, and with stones or jewels 10 of contrasting color, to indicate the snout 11 and with like colored jewels 12 to indicate the nose 13. The eyes 14 are made of

a central colored stone 15 and a plurality of outer stones 16 of a contrasting color. The 55 color of the stones 10, 12 and 16 is preferably black and the eye stones 15 red. Openings 18 are provided near the upper end of the mask to permit the ears 7 to protrude through the mask when it is secured on the head. 60

The mask when cut to the desired shape is drawn tightly over the head with the ears 7 protruding through the openings 18 and is attached by stitching or sewing same to the head by rows of stitches 20 at the top of the 65 head and by rows of stitches 21 underneath the head.

In Figs. 3 and 4, I have shown a modified form of my invention in which the snout is 70 covered by a section 21 of jewelled fabric, the ears 22 are formed of two ply leaf shaped sections of jewelled fabric and the eyes 23 are formed of circular jewelled sections of contrasting colored stones. 75

While I have described my invention as relating to scarf heads, I do not limit myself to such use as the head of my invention may be used for ornamenting or trimming any garment and in any part of same.

Many changes could be made in the above 80 construction and many apparently widely different embodiments of this invention could be made without departing from the scope thereof. It is intended that all matters contained herein in the above description or 85 shown in the accompanying drawings shall be interpreted as illustrative and not in a limiting sense. It is also to be understood that the language used in the following claims is merely intended to cover all the generic and 90 specific features of the invention herein described, and all statements of the scope of the invention which, as a matter of language, might be said to fall therebetween, and that materials, sizes and relativities of parts are 95 non-essential, except as called for in the claims.

From the above, it will be seen that I have provided means for highly ornamenting an animal head for use in fur scarfs and the like 100 and one that will greatly enhance the appearance and selling qualities of a garment having such an ornamental head.

Having described my invention, what I 105 claim as new and desire to secure by Letters Patent is:

1. In combination with a fur scarf animal head, an ornamental fabric of jewels secured thereto, in which the main features of the animal head are formed and accentuated by contrasting colored stones.
2. A mask adapted to be secured to the head of a fur scarf, comprising a jewelled fabric in which the eyes and snout are accentuated by contrasting colored stones.
3. A mask for fur scarf heads comprising a jewelled fabric studded with jewels of one color, a snout forming portion of stones of a different color, and eye simulating portions of stones of contrasting colors.
4. A jewelled mask for fur scarf heads, the 15 said mask having openings through which the ears of the head are adapted to protrude, the said mask consisting of a body portion studded with stones of a desired color, a snout forming portion of stones of a different 20 color, and eye simulating portions made of stones of contrasting colors.

GEORGE J. BARUCH.
